United States Patent Office.

J. D. AYERS, OF EAST GREENSBOROUGH, VERMONT.

Letters Patent No. 91,591, dated June 22, 1869.

IMPROVED CURTAIN-FIXTURE.

The Schedule referred to in these Letters Patent and making part of the same.

To all whom it may concern:

Be it known that I, J. D. AYERS, of East Greensborough, in the county of Orleans, and State of Vermont, have invented a new and useful Improvement in Curtain-Fixtures; and I do hereby declare that the following is a full, clear, and exact description thereof, which will enable those skilled in the art to make and use the same, reference being had to the accompanying drawings, forming part of this specification.

This invention relates to a new and useful improvement in the method of hanging window and other curtains, whereby they are rendered much more useful, and much less liable to get out of order than when hung in the ordinary manner.

The invention consists in the novel construction of the supporting-brackets, and also in attaching the hanging-brackets to the window-sash, as will be hereinafter more fully described.

Figure 1 represents a front view of a window, provided with curtain-fixtures according to my invention.

Figure 2 is a horizontal section, looking from the line *x x* of fig. 1.

Figure 3 is an edge view, showing the bracket projecting from the window.

Similar letters of reference indicate corresponding parts.

A represents the window-casing.

B is the sash.

C represents the brackets.

D represents the bracket-supporters.

In fig. 1, the pivots of the curtain-rod are seen, detached from the rod, and resting in the brackets.

In fig. 2, the rod is seen in red color.

e e represent the pivots.

f is the rod, and

g, the cord-pulley.

The brackets C are screwed into the sash, and extend out from the sash with two angles, as seen in the drawing, the outer ends of which support the rod-pivots *e e*.

A hole through the bracket receives the pivot *e*, and a slot in the other bracket receives the pivot *e'*, as in the common curtain-fixture.

The supporters D D are screwed or otherwise fastened to the sash, being formed with eyes, which enclose the brackets.

They act as braces from beneath, for supporting the bracket, as it reaches out from the sash, over the casing A, as seen in the drawing.

To the left-hand bracket, as seen in fig. 2, there is a small spring, *i*, attached, which is designed to bear upon the pivot *e* sufficiently hard to retain the curtain in any desired position, by the friction thus produced.

By attaching the curtain to the sash, the sash may be lowered to any desired point, and the curtain drawn so as to cover all the lower portion of the window, and still not interfere with the proper ventilation of the room.

By the use of the supports D D, the bracket is retained in place at all times, and prevented from getting loose, and thereby annoying housekeepers.

I claim as new, and desire to secure by Letters Patent—

The curtain-fixture, consisting of the right-angular brackets C, having the spring *i*, when supported upon the sash by means of the supports D, arranged as described, for the purpose specified.

J. D. AYERS.
